UNITED STATES PATENT OFFICE

DAVID E. WHITE, OF LA GRANGE, ILLINOIS, ASSIGNOR TO ROBERTS & SCHAEFER COMPANY, OF CHICAGO, ILLINOIS, A CORPORATION OF ILLINOIS

MATERIAL-STORAGE PLANT

Application filed May 2, 1927. Serial No. 188,121.

My invention relates to a ground storage plant for sand and relates to sand storage plants primarily for storage use. One object of my invention is to provide a sand storage plant of maximum capacity at minimum expense. Another object is the provision of a sand storage and drying plant wherein the sand may be readily and easily withdrawn from the storage pile and dried. Another object is the provision of means for withdrawing sand for drying and use, from the interior of an outdoor sand pile. Other objects will appear from time to time in the course of the specification and claims.

I illustrate my invention more or less diagrammatically in the accompanying drawings, wherein—

Figure 1 is a vertical section;

Figure 2 is a section taken on the line 2—2

20 of Figure 1; and

Figure 3 is a section taken on the line 3—3 of Figure 1.

Like parts are indicated by like symbols throughout the specification and drawings.

25 A indicates a supporting surface, which may be the outside ground surface and which may of course be leveled and surfaced to suit the particular needs. In many cases it is preferable to employ a smooth surfaced coating A¹ which may be of cement or the like. It will be understood that I do not wish to be limited to the use of such a surface. A² represents a pile of sand, herein shown as a cone the angle of which is determined by the 30 angle of repose of the sand.

Positioned within the pile is a dryer chamber indicated generally as B and having the foundations B¹, the walls B² and the roof B³. B⁴ indicates an opening in the side of said 40 chamber communicating with a tunnel B⁵ having the walls B⁶ and the roof B⁷. B⁸ is a door in the side of the chamber, herein shown as opposite the door B⁴, which may be closed in any suitable manner, for example by the 45 gates B⁹. The tunnel extends to and through the vertical retaining wall B¹⁰ which with the communicating retaining walls B¹², cuts out a space in the side of the otherwise conic completed pile. B¹⁴ is a ramp in line with 50 the door B⁸ and a platform grating B¹⁵ ex-

tending along the inner walls B² of the dryer chamber B.

The roof B³ of the chamber is provided with a plurality of hopper inlets C, herein shown as three in number. They are continued within the chamber itself for example by the surrounding apron C¹ to which are pivoted the gates C² controlled for example by the levers C³. Aligned with the inlets is the drying hopper C⁴ provided for example with the steam pipes C⁵ forming three separate hoppers. I do not wish to be limited to any specific dryer but I find a steam dryer satisfactory. The hoppers discharge to the inclined screens C⁶ within the hopper apron C⁷. It will be understood that the oversize and refuse passes by gravity downwardly across said screen and is discharged upon the receiving surface C⁸ for removal.

The hopper C⁷ feeds the dried cleaned sand 70 to the sand drum D, the passage of the sand to the drum being controlled by the valve D¹ which in turn is controlled by the lever D² and the counterweight D³. When the weight of the sand within the hopper overcomes the 75 counterweight sand pours into the drum and fills it. D⁴ indicates a compressed air line connected to the sand drum D at two points and controlled by a valve D⁵. D⁶ is a sand elevating pipe positioned within the sand 80 drum and in line with one inlet of the compressed air line D⁴, and continuing to any suitable bin or hopper not shown in the drawings. Upon the opening of the valve D⁵ the compressed air will blow the dried sand into 85 the sand elevating pipe, discharging it into the bin for storing.

E indicate tracks upon which may be positioned the sand car E¹ for discharge. E³ is a hopper beneath the track beneath which 90 is a loader or delivery means E⁴ the details of which form no part of the present invention. E⁵ is a pit beneath the hopper E³, into which extend the inclined conveyor tracks E⁶ along which rides the bucket E⁷. The 95 tracks are mounted upon any suitable supporting frame work, which include the inclined members E⁸, the vertical frame members E⁹ and the various transverse braces E¹⁰. E¹² indicates a platform at the top of the 100

frame work having a horizontal conveyor track E^{13} upon which ride the front wheels E^{14} of the bucket E^7 , and inclined tracks E^{15} in line with the tracks E^6 which are spaced further apart to accommodate the rear wheels E^{16} of the bucket. By this is meant that the bucket is suspended as shown in dotted lines in Figure 1.

10 G indicates any suitable flexible cable connected to the bale G^1 of the bucket E^7 . It passes about the head sheave G^2 and downwardly to the automatic hoist G^3 in the hoist house G^4 . The motive means and control of said hoist do not of themselves form part of 15 the present invention.

15 H indicates a vent pipe extending upwardly from the chamber B through the sand pile, and terminating at or above the level of the platform E^{12} .

20 It will be realized that whereas I have shown and described a practical and operative device nevertheless many changes might be made in the size, shape, number and disposition of parts without departing from the 25 spirit of my invention. I therefore wish my description and drawings to be taken as in a broad sense illustrative and diagrammatic rather than as limiting me to my specific showing.

30 The use and operation of my invention are as follows:

It has been customary in the past to store sand in relatively restricted enclosed hoppers or chambers or towers. I have developed a method of and apparatus for storing and handling sand which enormously increases the tonnage of sand which can be handled by a given plant, which greatly cuts down the initial expense of the installation, 40 and which provides an installation which can be operated at large capacities and at minimum cost. I provide an enclosed chamber B adjacent the sand receiving point. The sand may be delivered from the cars to any 45 suitable conveyor, herein shown as a bucket conveyor, and may be discharged above the chamber B . The result, in the particular embodiment of my invention herein shown, is a conic pile which covers and surrounds the 50 drying chamber. Access is had to the chamber through the tunnel B^5 and ventilation is maintained by means of the vent pipe H which extends above the maximum height of the pile. In the typical installation herein shown the pile may contain, for example, 55 2500 tons of sand. The apex of the pile and the portion of the pile directly overlying the chamber, to the quantity of say 400 tons, may be permitted to flow downwardly by gravity 60 through the inlets C in the roof B^3 of the chamber. These inlets may be controlled in any suitable manner, for example by the pivot gates C^2 and the sand so delivered is permitted to pass to sand dryers for drying. 65 The sand, when dried, flows across the in-

clined screen C^6 and the dried sand passes to the sand drum. Sand from the sand drum is propelled, as earlier described for disposal and use exteriorly of the chamber and pile.

When the upper 400 tons have been drawn off through the sand gates the sand above the roof B^3 of the container amounting to say 50 tons, may be shoveled into the sand gates. The sand pile may be replenished and it may, under some circumstances, prove desirable to maintain continuously above the chamber a sufficient head of sand to permit gravity withdrawal. On the other hand, if the height of the sand pile is lowered the gate B^9 may be opened and sand may be brought in therethrough for delivery to the drying hoppers. Preferably a passageway is shoveled through the pile, which by this time has become a ring about the chamber, and the sand may be brought in by wheelbarrow up the ramp B^{14} and along the platform B^{15} within the chamber, for delivery to the drying hoppers.

70 I claim:

1. The method of handling sand which includes piling said sand, laterally unconfined, above and about a sand drying area, 75 interiorly withdrawing said sand and drying it, within said pile, and removing it from the interior of the pile, when dried, for use exteriorly of such pile.

2. The method of handling sand which includes forming a pile of laterally unconfined sand, drying sand within the interior of such pile, and withdrawing the dried sand from such pile.

3. The method of handling sand which includes forming a pile of laterally unconfined sand, drying sand within the interior of such pile, separating the refuse from such sand, after the drying of the sand and before it is withdrawn and withdrawing the dried and cleaned sand from the interior of such pile.

4. The method of handling sand which includes conveying sand, laterally unconfined, above a drying area, delivering it by gravity thereabove and thereabout to make a pile the form of which is determined by the angle of repose of the sand, and withdrawing and drying sand from the interior of such pile.

5. The method of handling sand which includes forming a pile of laterally unconfined sand, interiorly withdrawing, by gravity, the uppermost sand of the pile and drying it in a drying zone positioned within and enclosed by the complete pile, and subsequently conveying the sand in the lower portions of said pile laterally to said drying zone, when the upper part of the pile has been withdrawn and dried.

6. The method of handling sand which includes forming a pile of sand, interiorly withdrawing, by gravity, the uppermost sand of the pile and drying it in a drying zone positioned within and enclosed by the complete pile, cleaning the sand so withdrawn in 120 125 130

the interior of said pile, and subsequently conveying the sand in the lower portion of said pile laterally to said drying and cleaning zone after the uppermost sand of the pile has been exhausted.

5 7. A sand handling installation which includes a conveyor adapted to receive sand and to release it above the pile to be formed, a housing positioned beneath the point of discharge of such conveyor, and, in normal use of the installation, adapted to be surrounded by the pile so formed, a sand inlet in such housing, and means for controlling the passage of sand therethrough, a sand dryer 10 within the housing, adapted to receive and dry the sand admitted within the housing.

15 8. A sand handling installation which includes a conveyor adapted to receive sand and to release it above the pile to be formed, a housing positioned beneath the point of discharge of such conveyor, and, in normal use of the installation, adapted to be surrounded by the pile so formed, a sand inlet in such housing, and means for controlling the passage of sand therethrough, a sand dryer 20 within the housing, adapted to receive and dry the sand admitted within the housing, and cleaning means within the housing.

25 9. A sand handling installation which includes a conveyor adapted to receive sand and to release it above the pile to be formed, a housing positioned beneath the point of discharge of such conveyor, and, in normal use of the installation, adapted to be surrounded by the pile so formed, a sand inlet in such housing, and means for controlling the passage of sand therethrough, a sand dryer 30 within the housing, adapted to receive and dry the sand admitted within the housing, an air-tight container and means for delivering thereto the dried sand and means for pneumatically exhausting sand from said container.

35 10. A sand handling installation which includes a conveyor adapted to receive sand and to release it above the pile to be formed, a housing positioned beneath the point of discharge of such conveyor, and, in normal use of the installation, adapted to be surrounded by the pile so formed, a sand inlet in such housing, and means for controlling the passage of sand therethrough, a sand dryer 40 within the housing, adapted to receive and dry the sand admitted within the housing, cleaning means within the housing, an air-tight container and means for delivering thereto the dried sand and means for pneumatically exhausting sand from said container.

45 11. A sand handling installation which includes a track, a receiving pit therebeneath, a conveyor and a conveyor bucket associated therewith and adapted to penetrate beneath 50 said track and to receive material discharged

from said track, means for elevating said bucket and for discharging it adjacent the upper limit of its elevation to form a loose, laterally unconfined pile of sand, a sand dryer chamber positioned beneath the point 55 of discharge of said conveyor bucket, a sand inlet in said chamber and means for controlling the passage of sand therethrough, a sand dryer within the chamber, adapted to receive and dry the sand admitted into the 60 chamber, and means for conveying the dried sand.

12. A sand handling installation which includes a sand dryer chamber, a pile of laterally unconfined sand thereabout and thereabove, a sand inlet in said chamber and means for controlling the passage of sand therethrough from the pile, a sand dryer 65 within the chamber, adapted to receive and dry the sand admitted into the chamber and means for conveying the dried sand from said chamber.

13. A sand handling installation which includes a sand drying chamber, a pile of laterally unconfined sand thereabout and thereabove, a sand inlet in the upper portion of said chamber adapted to permit the passage of sand by gravity therethrough, and means for controlling the passage of sand therethrough from the pile, an additional inlet 70 in the side of the chamber, a sand dryer within the chamber adapted to receive and dry the sand admitted into the chamber, and means for conveying the dried sand from said chamber.

14. A sand handling installation which includes a sand drying chamber, a pile of sand thereabout and thereabove, a sand inlet in the upper portion of said chamber adapted to permit the passage of sand by gravity therethrough, and means for controlling the passage of sand therethrough from the pile, an additional inlet in the side of the chamber, a sand dryer within the chamber adapted to receive and dry the sand admitted into the chamber, means for cleaning the sand, and means for conveying the dried and cleaned sand from said chamber.

15. A sand handling installation which includes a sand dryer chamber, a passage extending to said chamber, means for depositing a pile of laterally unconfined sand above and about said chamber, a sand inlet in said chamber and means for controlling the passage of sand therethrough, a sand dryer 110 within said chamber and means for conveying the dried sand from said chamber.

Signed at Chicago, county of Cook, and State of Illinois, this 21st day of April, 1927.

DAVID E. WHITE. 125
